ATTORNEY

UNITED STATES PATENT OFFICE

EARL O. MINOR, OF NEW YORK, N. Y.

MACHINE FOR REMOVING AND REPLACING PISTON WRIST PINS

Application filed May 21, 1930. Serial No. 454,427.

This invention relates to machines for removing and replacing piston wrist pins and is especially adapted for use with pistons wherein the pins are driven from and into 5 position.

Another object of the present invention is the provision of means for securely holding and reinforcing the walls of a piston while the wrist pins are being removed and replaced, and thus eliminate danger of cracking or distorting the walls, a common result when the pins are driven.

Another object of the invention is the provision of a machine in which a single 15 operation will remove an old pin and replace a new one in an efficient and expeditious manner, and which is capable of use with wrist pins having interlocking connection with connecting rod bearings.

With the above and other objects in view, the invention further includes the following 20 novel features and details of construction, to be hereinafter more fully described, illustrated in the accompanying drawings and 25 pointed out in the appended claims.

In the drawings:—

Figure 1 is a top plan view of the machine with a piston in place and its connecting rod shown in section.

Figure 2 is a section on the line 2—2 of 30 Figure 1.

Figure 3 is a section on the line 3—3 of Figure 1.

Figure 4 is a section on the line 4—4 of 35 Figure 2.

Figure 5 is an elevation of the reinforcing member.

Figure 6 is a view at right angles to Figure 5.

Figure 7 is a detail view of an aligning 40 bar for use with the invention.

Figure 8 is a detail view of the pilot.

Figure 9 is a like view of the wrist pin carrier.

Referring to the drawings in detail where 45 in like characters of reference denote corresponding parts, the reference character 10 indicates the base of the machine, upon which is removably mounted a piston holder 11. This holder is in the form of a hollow

cylinder and is removably attached to the base by means of bolts 12. The holder is vertically split as shown at 13 and extending from the holder upon opposite sides of the split are lugs 14. A screw 15 passes 55 through these lugs and is provided with an operating handle 16, by means of which the size of the bore of the cylinder may be adjusted to accommodate pistons of different sizes within a certain radius. The holder 11 60 may be removed from the base and another holder substituted for pistons of other sizes.

The holder 11 is adapted to receive a piston 17, as shown in Figures 2, 3 and 4 of the drawings and the wrist pin bearings are 65 brought into axial alignment with openings 18 provided in the holder. A suitable tool or aligning bar 19 may be employed for this purpose, although this bar is not essential. The bar 19 is provided with a reduced extremity 20 which is adapted to pass through one of the openings 18 into the wrist pin 21 carried by the piston, and will hold the piston in proper position during the 70 initial operation of the machine.

A reinforcing member 22 is inserted within the piston and acts to back up and reinforce the piston walls, so that pressure necessary in removing or inserting wrist pins will not injure the walls of the piston. This 75 reinforcing member is slotted as shown at 23 for the accommodation of a connecting rod 24 and its bearing 25.

Rising from the base 10 is a bearing member 26, which is provided with an internally threaded opening 27. A feed screw 28 passes through this opening and threadedly engages the bearing, the screw being axially aligned with the openings 18 of the piston holder. The screw 28 is provided with an operating handle 29 at its outer end. The inner end of the screw is provided with a socket 30 which receives a reduced extremity 31 provided upon one end of a wrist pin carrier 32. 80 This carrier is provided with a collar 33 which bears against the end of the screw 28 and provides means whereby the screw may rotate without rotating the pin carrier. The pin carrier has its opposite end beveled and 85

100

provided with a shoulder 34 for engagement by one end of a wrist pin 21a, the latter representing the new wrist pin to be inserted.

- 5 The pin carrier 32 is also socketed at one end as shown at 35 and this socketed end receives the reduced end 36 of a pilot 37. This pilot is tapered and is adapted to be inserted in the end of the wrist pin 21. A head 38 10 of relatively large diameter is provided upon the end of the pilot 37 and the inner end of this head provides a shoulder 39 which abuts the adjacent end of the pin 21a. The outer end of the head 38 is semi-spherical as 15 shown at 40.

After the piston has been positioned within the holder and the openings 18 and the wrist pin have been brought into axial alignment, the screw 28 is fed inward with the 20 substitute wrist pin 21a mounted upon the carrier and the pilot positioned in advance of the wrist pin. The head 38 of the pilot engages the end of the old wrist pin 21 and presses the latter outward, the new wrist pin 25 following the head into and through the piston and connecting rod bearings.

In the form of connecting rod bearings shown, a metal ring 41 is employed, and this ring must be expanded to permit the pin 21a 30 to be inserted. This expanding action is effected by the rounded end 40 of the head 38 of the pilot, as will be seen from an inspection of Figure 2 of the drawings.

From the foregoing description and accompanying drawings, it will be seen that the piston is securely held in proper position with its walls properly reinforced, so that the pressure necessary for removing an old pin and inserting a new pin may be employed 40 without danger to the piston.

Where the metal rings 41 are used, the pin will be provided with circumferential notches 42. The reinforcing member 22 is provided with a handle 43.

45 It is preferred to heat the piston by submerging the same in hot water prior to the removal and insertion of the pins.

The invention is susceptible of various changes in its form, proportions and minor 50 details of construction and the right is herein reserved to make such changes as properly fall within the scope of the appended claims.

Having described the invention what is claimed is:—

- 55 1. In a wrist pin removing and replacing machine, a piston holder having openings therein and adapted to receive a piston, a reinforcing member adapted to be inserted 60 within the piston to engage the walls thereof, a wrist pin carrier mounted for longitudinal movement, means to move the carrier, and means supported by the carrier and located in advance of a wrist pin mounted upon said 65 carrier to engage and force an old wrist pin

from the piston and provide a pilot for the carrier mounted wrist pin.

2. In a wrist pin removing and replacing machine, a piston holder having openings therein and adapted to receive a piston, a reinforcing member adapted to be inserted 70 within the piston to engage the walls thereof, a wrist pin carrier mounted for longitudinal movement, means to move the carrier, and a semi-spherical headed pilot supported by the carrier and located in advance of a wrist pin mounted upon said carrier to engage and force an old wrist pin from the piston and provide a lead for the carrier mounted wrist pin.

3. In a wrist pin removing and replacing machine, a base, a member rising from the base and having a socket therein to receive and provide a holder for the piston, said member having oppositely located openings 85 therein, a reinforcing member adapted to be inserted within the piston to engage the walls thereof, a bearing member rising from the base, a feed screw engageable with said member and movable toward and away from the piston holder, a wrist pin carrier mounted at the outer end of the screw, and means supported by the carrier in advance of a wrist pin mounted upon said carrier to engage and force an old wrist pin from the piston and provide a pilot for the carrier mounted wrist pin.

4. In a wrist pin removing and replacing machine, a base, a member rising from the base and having a socket therein to receive 100 and provide a holder for a piston, said member having oppositely located openings therein, a reinforcing member adapted to be inserted within the piston to engage the walls thereof, a bearing member rising from the base, a feed screw engageable with said member and movable toward and away from the piston holder and having an axially disposed socket in one end, a wrist pin carrier having one end reduced and engageable 105 within the said socket and its other end adapted to be received within a wrist pin, a shoulder upon the carrier for engagement by one end of said pin, and means supported by the carrier and located in advance of a wrist pin mounted upon said carrier to engage and force an old wrist pin from the piston and provide a pilot for the carrier mounted wrist pin.

45 5. In a wrist pin removing and replacing machine, a wrist pin holder including a split hollow cylindrical member adapted to receive a piston, means engaging the holder upon opposite sides of the split to adjust the diameter of the holder to accommodate pistons of different diameters, a reinforcing member adapted to be inserted within the piston to engage the walls thereof, a wrist pin carrier mounted for longitudinal movement, means to move the carrier, and means supported by the carrier and located in advance of a wrist pin mounted upon said carrier to engage and force an old wrist pin from the piston and provide a pilot for the carrier mounted wrist pin.

5. In a wrist pin removing and replacing machine, a wrist pin holder including a split hollow cylindrical member adapted to receive a piston, means engaging the holder upon opposite sides of the split to adjust the diameter of the holder to accommodate pistons of different diameters, a reinforcing member adapted to be inserted within the piston to engage the walls thereof, a wrist pin carrier mounted for longitudinal movement, means to move the carrier, and means supported by the carrier and located in advance of a wrist pin mounted upon said carrier to engage and force an old wrist pin from the piston and provide a pilot for the carrier mounted wrist pin.

the carrier and located in advance of a wrist pin mounted upon said carrier to engage and force an old wrist pin from the piston and provide a pilot of the carrier mounted wrist pin.

5 In testimony whereof I affix my signature.

EARL O. MINOR.
